MODULATED-CARRIER SIGNAL RECEIVER

Harold M. Lewis, Great Neck, N. Y., assignor to
Hazelton Corporation, a corporation of Delaware

Application September 25, 1939, Serial No. 296,339

12 Claims. (CL 250—20)

This invention relates generally to a modulated-carrier signal receiver including means for selecting a carrier having a given characteristic type of modulation representing a desired signal and subject to undesired modulation of a second characteristic type, in which means are provided for substantially eliminating the effect of the undesired signal disturbances in the reproduction of the characteristic type of modulation representing the desired signal. While the invention is of general application, it is of particular utility in a modulated-carrier signal receiver adapted for the reception of a frequency-modulated signal which is also subject to undesired amplitude modulation.

Receivers for the reception of a frequency-modulated wave generally incorporate therein an arrangement for substantially eliminating amplitude modulation of the received signal and for thereafter applying the signal to an analyzer circuit wherein the frequency-modulation components are detected and converted into amplitude modulation for detection by means of a conventional amplitude detector. In receivers of this type, it is, of course, essential to eliminate all incidental and undesired amplitude modulation. Limiters have commonly been utilized for this purpose at various points in the signal-translating channel of the receiver. However, such limiters do not provide an entirely satisfactory operation for the reason that the circuits of the limiters generally comprise vacuum tubes operated beyond their upper or lower cutoff points to eliminate amplitude modulation of the translated signal and, due to the curved input voltage-output current characteristic of such limiter tubes in the region of either cutoff point, an appreciable distortion is effected within the tube which, in turn, may be reproduced as an undesired signal disturbance.

It is an object of the present invention, therefore, to provide an improved modulated-carrier signal receiver adapted to receive a carrier having a first characteristic type of modulation representing a desired signal and subject to undesired modulation of a second characteristic type.

It is a further object of the invention to provide an improved modulated-carrier signal receiver adapted to receive a frequency-modulated signal and including means for substantially eliminating the effect of undesired amplitude modulation.

In accordance with the invention, therefore, a modulated-carrier signal receiver includes means for selecting a carrier wave having a first

characteristic type of modulation representing a desired signal and subject to undesired modulation of a second characteristic type, a carrier-frequency signaling-translating stage, and means for selectively detecting and utilizing the selected carrier modulation of the first type to reproduce the desired signal. There is further provided means for selectively detecting and utilizing only the selected carrier modulation of the second type instantaneously to control the response characteristic of the carrier-frequency signal-translating stage inversely in accordance therewith to reduce the effects of the undesired signal modulation. In a preferred embodiment 10 of the invention, the detected components of the selected carrier modulation of the second type are utilized instantaneously and inversely to control the gain of one or more amplifier tubes in the carrier-frequency signal-translating channel 15 in the receiver to reduce the effects of the undesired signal modulation.

For a better understanding of the present invention, together with other and further objects thereof, reference is had to the following description taken in connection with the accompanying drawing and its scope will be pointed out in the appended claims.

Fig. 1 of the drawing is a circuit diagram, partly schematic, of a complete superheterodyne receiver adapted to receive a frequency-modulated carrier wave and comprising therein an arrangement in accordance with the invention for suppressing undesired amplitude-modulation components of the received signal, while each of 30 35 Figs. 2 and 3 illustrates a different embodiment of the invention.

Referring now more particularly to Fig. 1 of the drawing, there is shown a circuit diagram, partly schematic, of a superheterodyne receiver 40 embodying the invention and adapted to receive a carrier wave having a first characteristic type of modulation representing a desired signal and subject to undesired modulation of a second characteristic type. Specifically, the receiver is adapted 45 to receive a frequency-modulated carrier wave which is subject to undesired amplitude modulation. Briefly described, the receiver comprises a radio-frequency amplifier 10 having input terminals connected to a doublet antenna 11, 12 and 50 output terminals coupled to a modulator or frequency-changer unit 13 having associated therewith a local oscillator 14. Connected in cascade with the output circuit of modulator 13, in the order named, are an intermediate-frequency amplifier 15 of one or more stages, a second inter-

mediate-frequency amplifier 16, an intermediate-frequency amplifier 17, a frequency-modulation detector 18, an audio-frequency amplifier 19 of one or more stages, and a sound reproducer 20. The stages 10, 13, 15, 16, and 17 thus comprise carrier-frequency signal-translating stages.

Considering first the operation of the receiver as a whole, without regard to the details of the arrangement of the present invention, per se, a desired received frequency-modulated signal is selected and amplified in radio-frequency amplifier 10 and converted to a modulated-carrier intermediate-frequency signal by modulator or frequency changer 13. The signal as thus converted is further amplified in intermediate-frequency amplifiers 15, 16, and 17 and detected by the frequency-modulation detector 18, thereby producing the audio-frequency modulation components which are, in turn, amplified by audio-frequency amplifier 19 and reproduced by the sound reproducer 20. Thus, the frequency-modulation detector 18, the audio-frequency amplifier 19, and the sound reproducer 20 comprise means for selectively detecting and utilizing the selected-carrier modulation of the type representing the desired signal to reproduce the latter.

Referring now more particularly to the details of the system comprising the present invention, the stage of intermediate-frequency amplification 16 includes therein a vacuum tube 25 having input terminals coupled through transformer 26 to the output terminals of intermediate-frequency amplifier 15 and output terminals coupled to the input terminals of intermediate-frequency amplifier 17. A suitable self-bias arrangement, including cathode-resistor 27, by-passed for high-frequency signals by condenser 28, is provided for vacuum tube 25. In order to derive the amplitude-modulation components of the received signal, there is provided means coupled to the signal-translating channel 15 for selectively detecting the undesired amplitude-modulation components of the received carrier signal comprising a diode detector 29 coupled to the output circuit of intermediate-frequency amplifier 15 by means of a transformer 30. Detector 29 comprises a load circuit including delay-bias source 29' and resistor 31, by-passed for carrier-frequency signals by condenser 32. The amplitude-modulation components of the signal are thus derived from load resistor 31 and are applied positively to a direct coupled vacuum-tube amplifier 33 through an inductance 34. A suitable biasing arrangement comprising cathode-resistor 35, by-passed for carrier-frequency signals by condenser 36, is provided for vacuum tube 33 while the control-grid circuit includes a resistor 37, by-passed by condenser 38. It follows that elements 31, 32, 34, 37, 38 effectively comprise a properly terminated low-pass filter circuit to develop the signal voltage across the input circuit of tube 33. Suitable operating potentials are provided for tubes 25 and 33 in a manner well understood in the art.

The signal output of tube 33 is utilized to control the gain of the signal-translating channel of the receiver inversely in accordance with the amplitude-modulation components of the received signal, thereby to cause an amplitude de-modulation of the received signal and effectively reduce its resultant amplitude modulation to an unobjectionable value. For this purpose, the signal output of tube 33 is applied to the screen grid 40 of tube 25. The output voltage of tube

33 furthermore may be applied in a similar manner to one or more of the tubes in radio-frequency amplifier 10, modulator 13, and intermediate-frequency amplifiers 15 and 17, and is illustrated 5 as being applied to all of these tubes by way of a conductor 41.

Oscillator 14 comprises a vacuum tube 42 having a frequency-determining circuit 43, 44 and an oscillation-sustaining feed-back circuit including a condenser 45 and an inductance 46 inductively coupled to inductance 43. The output circuit of the oscillator 14 is coupled to modulator 13 through an inductance 47 inductively coupled to inductance 43. The amplitude-modulation components of the received signal derived from the output circuit of vacuum tube 33 are shown as applied also to the screen-grid electrode 49 of vacuum-tube oscillator 42. The frequency-modulation translating channel is preferably designed for a wide band frequency-modulation receiver to pass a wide frequency range, while the circuits including tubes 29 and 33 are designed to pass a relatively narrow band, preferably of the same order of magnitude as the band width of the desired audio-frequency signals, since it may not be necessary to balance out amplitude-modulation components outside the audio-frequency range.

In considering the operation of the portion of 30 the system of Fig. 1 comprising the present invention, it will be seen that the amplitude-modulation components of the received signal are derived from the load circuit of detector 29 and amplified by vacuum tube 33 to provide a signal 35 output therefrom which varies in accordance with the instantaneous values of the amplitude-modulation components of the received signal. These amplitude-modulation components are applied to the screen grid of vacuum tube 25 in such 40 a way as to vary the gain thereof inversely in accordance with the amplitude of the amplitude-modulation components of the received signal, thereby to demodulate or reduce the percentage of amplitude modulation of the received signal. 45 The output signal of vacuum tube 25, as applied to intermediate-frequency amplifier 17, therefore, has the amplitude-modulation components thereof materially reduced.

The tubes of radio-frequency amplifier 10, modulator 13, and intermediate-frequency amplifiers 15 and 17 may be controlled in a similar manner, thereby to eliminate substantially all amplitude-modulation components of the received signal as applied to the frequency-modulation detector 18, thereby eliminating the necessity for limiter arrangements in the signal-translating channel of the receiver comprising vacuum tubes operated through their cutoff points with their attendant disadvantages. Also, the output of 55 vacuum tube 33 is applied to the screen electrode of oscillator tube 42 to vary the amplitude of the output thereof inversely in accordance with the amplitude of the amplitude-modulation components of the received signal. This also has the effect of decreasing the amplitude-modulation components of the received signal as applied to the intermediate-frequency channel of the receiver. It will be seen that the control of the 60 gain of the signal-translating stages 10, 13, and 15 occurs at points preceding the point to which the detector 29 is coupled to the signal-translating channel and, therefore, is regressive as applied to these units. On the other hand, the 65 control of the gain of tube 25 and intermediate- 70

frequency amplifier 17 occurs at points succeeding the point at which the detector 29 is coupled to the signal-translating channel and is progressive as applied to these signal-translating stages, which condition is necessary for a substantially complete elimination of amplitude modulation of the received signal. Thus, the detector 29 and the control connections to the carrier-frequency signal-translating stages 10, 13, and 15-17, inclusive, comprise means for selectively detecting and utilizing only the selected-carrier modulation of the type representing undesired amplitude modulation to control or reduce the amplitude response or gain characteristic of the carrier-frequency signal-translating stages 10, 13, and 15-17, inclusive, in accordance with instantaneous values thereof to reduce the effects of the undesired amplitude modulation of the received signal effectively by amplitude demodulation of the signal.

It will be seen that, inasmuch as the control circuit including tubes 29 and 33 is effective at very low frequencies, the system of Fig. 1 is effective also to provide an automatic volume control for the receiver, and, due to the bias provided by source 29', the amplitude of the input to detector 18 is maintained within a relatively narrow range for a wide range of input amplitudes of the receiver, which may vary at a very low frequency.

The embodiment of the invention illustrated in Fig. 2 is generally similar to that illustrated in Fig. 1 and similar circuit elements have identical reference numerals. The embodiment of the invention illustrated in Fig. 2 differs from that of Fig. 1 primarily in that the amplitude-modulation components of the received signal are applied to the suppressor electrode 51 of tube 25 rather than to the screen-grid electrode 40 as in Fig. 1. Inasmuch as amplitude-modulation components of the same polarity are necessary for a like effect upon the gain of vacuum tube 25 when applied to the suppressor electrode 51, the stage of intermediate-frequency amplification 16 of Fig. 2 includes an amplifier 53, corresponding to amplifier 33 of Fig. 1, which is provided with a cathode-resistor 58 from across which the output voltages of the amplifier are derived and the detector 29 and source 29' are included in the circuit with reversed polarity. These amplitude-modulation components are applied through a suitable low-pass filter including inductance 60 to the suppressor electrode 51 of tube 25 to control the gain thereof in a manner substantially similar to that described for Fig. 1, rendering a detailed description of the operation of the circuit of Fig. 2 unnecessary. Inasmuch as it is desirable that the amplitude-modulation components applied to grid 51 of tube 25 be substantially in phase with corresponding components applied through transformer 26 to the input electrode of tube 25, it may become necessary to provide some arrangement for adjusting the relative phase of these signals. Such compensating network or phase changer 61 is shown in the circuit of Fig. 2 coupled between inductance 60 and grid 51. Phase changer 61 may be of conventional design.

In Fig. 3 there is illustrated a further modification of the invention wherein elements which are similar to the elements of the preceding figures have identical reference numerals. The circuit of Fig. 3 differs from that of Fig. 2 mainly in that amplifier 53 and phase changer 61 are omitted and in that the output potentials of

rectifier 28 are applied directly to the input circuit of vacuum tube 25.

In considering the operation of the circuit of Fig. 3, it will be seen that the amplitude-modulation components of the desired received signal are derived across load circuit 31 and are applied to the input circuit of vacuum tube 25 with a polarity opposite to that of corresponding amplitude-modulation components applied to the input circuit of tube 25 directly through transformer 26. The operation of the circuit of Fig. 3 is otherwise similar to that of Fig. 2, rendering a detailed description of the operation thereof unnecessary.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A modulation-carrier signal receiver adapted to receive a carrier wave having a first characteristic type of modulation representing a desired signal and subject to undesired modulation of a second characteristic type comprising, a carrier-frequency signal-translating stage, means for selectively detecting and utilizing said selected-carrier modulation of said first type to reproduce the desired signal, and means for selectively detecting and utilizing only said selected-carrier modulation of the second type to control the response characteristic of said carrier-frequency signal-translating stage in accordance with instantaneous values thereof to reduce the effects of said undesired signal modulation.
2. A modulated-carrier signal receiver having a signal-translating channel including a carrier-frequency stage and adapted to receive a carrier wave having a first characteristic type of modulation representing a desired signal and subject to undesired modulation of a second characteristic type comprising, means for selectively detecting and utilizing said selected-carrier modulation of said first type to reproduce the desired signal, and means for selectively detecting and utilizing only said selected-carrier modulation of said second type to control the gain of said carrier-frequency stage inversely in accordance with the instantaneous values thereof to reduce the effects of said undesired signal modulation.
3. A modulated-carrier signal receiver having a signal-translating channel including a carrier-frequency stage and adapted to receive a carrier wave having a first characteristic type of modulation representing a desired signal and subject to undesired modulation of a second characteristic type comprising, means for selectively detecting and utilizing said selected-carrier modulation of said first type to reproduce the desired signal, and means for selectively detecting and utilizing only said selected-carrier modulation of said second type instantaneously to control said carrier-frequency stage in accordance with the instantaneous values thereof to provide demodulation of the received signal in accordance therewith.
4. A modulated-carrier signal receiver including a signal-translating channel including a carrier-frequency stage and adapted to receive a carrier wave having a first characteristic type

of modulation representing a desired signal and subject to undesired modulation of a second characteristic type comprising, means for selectively detecting and utilizing said selected-carrier modulation of the first type to reproduce the desired signal, means coupled to said signal-translating channel for selectively detecting the modulation components of said selected-carrier modulation of the second type, and means for utilizing said detected modulation components to reduce the gain of said carrier-frequency stage in accordance with the instantaneous values thereof at a point succeeding the point to which said last-mentioned detecting means is coupled, thereby to reduce the effects of said undesired signal modulation.

5. A modulated-carrier signal receiver including a signal-translating channel including a carrier-frequency stage adapted to receive a carrier wave having a first characteristic type of modulation representing a desired signal and subject to undesired modulation of a second characteristic type comprising, means for selectively detecting and utilizing said selected-carrier modulation of the first type to reproduce said desired signal, means coupled to said signal-translating channel for selectively detecting the modulation components of said selected-carrier modulation of said second type, and means for utilizing said detected modulation components to reduce the gain of said carrier-frequency stage in accordance with the instantaneous values thereof at a point preceding the point to which said last-mentioned detecting means is coupled, thereby to reduce the effects of said undesired signal modulation.

6. A modulated-carrier signal receiver including a signal-translating channel including carrier-frequency stages adapted to receive a carrier wave having a first characteristic type of modulation representing a desired signal and subject to undesired modulation of a second characteristic type comprising, means for selectively detecting and utilizing said selected-carrier modulation of the first type to reproduce said desired signal, means coupled to said signal-translating channel for detecting the modulation components of said selected-carrier modulation of said second type, and means for utilizing said detected modulation components to reduce the gain of said carrier-frequency stages in accordance with the values thereof at a point preceding and at a point succeeding the point to which said last-mentioned detecting means is coupled, thereby to reduce the effects of said undesired signal modulation.

7. A modulated-carrier signal receiver of the superheterodyne type including a local oscillator adapted to receive a carrier wave having a first characteristic type of modulation representing a desired signal and subject to undesired modulation of a second characteristic type comprising, means for selectively detecting and utilizing said selected-carrier modulation of said first type to reproduce the desired signal, means for selectively detecting said selected-carrier modulation of said second type, and means for utilizing the detected modulation components of said second type to vary the amplitude of the output of said oscillator in accordance with the instantaneous values thereof and thereby to reduce the effects of said undesired signal modulation.

8. A modulated-carrier signal receiver including a signal-translating channel adapted to receive a carrier wave having a first characteristic

type of modulation representing a desired signal and subject to undesired modulation of a second characteristic type comprising, carrier-frequency amplifier means in said channel including a vacuum tube, means for selectively detecting and utilizing said selected-carrier modulation of said first type to reproduce the desired signal, means for selectively detecting only said selected-carrier modulation of the second type, and means for applying said detected components of said second type to said tube to reduce the gain of said carrier-frequency amplifier inversely in accordance with the instantaneous values of said components, thereby to reduce the effects of said undesired signal modulation.

9. A modulated-carrier signal receiver adapted to receive a carrier wave having a frequency modulation representing a desired signal and subject to undesired amplitude modulation comprising, a carrier-frequency signal-translating stage, means for selectively detecting and utilizing said selected-carrier frequency modulation to reproduce the desired signal, and means for selectively detecting and utilizing only said selected-carrier amplitude modulation to control the response characteristic of said carrier-frequency signal-translating stage inversely in accordance with the instantaneous values thereof, whereby the effects of said undesired signal modulation are materially reduced.

10. A modulated-carrier signal receiver adapted to receive a carrier wave having a frequency modulation representing a desired signal and subject to undesired amplitude modulation comprising, a carrier-frequency signal-translating stage, means for selectively detecting and utilizing said selected-carrier frequency modulation to reproduce the desired signal, and means for selectively detecting and utilizing said selected-carrier amplitude modulation to control the response characteristic of said carrier-frequency signal-translating stage inversely in accordance with the instantaneous values thereof and for varying said characteristic inversely in accordance with the amplitude of the signal input to said receiver, whereby the effects of said undesired signal modulation are materially reduced and an automatic gain control is provided for said receiver.

11. A modulated-carrier signal receiver adapted to receive a carrier wave having a frequency modulation representing a desired signal and subject to undesired amplitude modulation comprising, a carrier-frequency signal-translating stage, means for selectively detecting and utilizing said selected-carrier frequency modulation to reproduce the desired signal, and means including a delay-bias source for selectively detecting and utilizing only said selected-carrier amplitude modulation to control a response characteristic of said carrier-frequency signal-translating stage inversely in accordance with the instantaneous values thereof and for varying said characteristic inversely in accordance with the amplitude of the signal input to said receiver, whereby the effect of said undesired signal modulation is materially reduced and an automatic gain control is provided for said receiver.

12. A wide band frequency-modulation signal receiver adapted to receive a carrier wave having a frequency modulation corresponding to a wide frequency range representing a desired signal and subject to undesired amplitude modulation comprising, a carrier-frequency signal-translating stage, means for selectively detect-

ing and utilizing said selected-carrier frequency modulation to reproduce the desired signal, and means for selectively detecting and utilizing only said selected-carrier amplitude modulation of a relatively narrow frequency band corresponding in order of band width to that of the band width of the desired signal to be reproduced to control

the response characteristic of said carrier-frequency signal-translating stage inversely in accordance with the instantaneous values thereof, whereby the effects of said undesired signal modulation are materially reduced.

HAROLD M. LEWIS.
